PLASTIC PAIL

Robert D. Moore, Los Angeles, Calif., assignor to Carnation Company, Los Angeles, Calif., a corporation of Delaware

Filed Mar. 21, 1966, Ser. No. 1,565

Term of patent 14 years

(Cl. D58—17)

FIG. 1 is a view in perspective of a plastic pail, showing my new design.

FIG. 2 is a view in elevation thereof looking at the upper right-hand portion of FIG. 1.

FIG. 3 is a view in elevation thereof looking at the lower right-hand corner of FIG. 1.

FIG. 4 is a top plan view thereof, and

FIG. 5 is a bottom plan view thereof.

FIG. 6 is a fragmentary view in section taken along the line 6—6 in FIG. 4.

I claim:

The ornamental design for a plastic pail, substantially as shown.
